UNITED STATES PATENT OFFICE.

HENRY C. BECKWITH, OF RAVENNA, OHIO, ASSIGNOR TO THE JOHN F. BYERS MACHINE COMPANY, OF RAVENNA, OHIO, A CORPORATION OF OHIO.

HOISTING MECHANISM.

Application filed August 22, 1919. Serial No. 319,131.

To all whom it may concern:

Be it known that I, HENRY C. BECKWITH, a citizen of the United States, and a resident of Ravenna, county of Portage, and State 5 of Ohio, have invented a new and useful Improvement in Hoisting Mechanism, of which the following is a specification, the principle of the invention being herein explained and the best mode in which I have 10 contemplated applying that principle, so as to distinguish it from other inventions.

The present invention, relating, as indicated, to hoisting mechanism, is particularly concerned with an improved portable crane 15 and with certain novel features thereof, which will be hereinafter described. To the accomplishment of the foregoing and related ends, said invention, then, consists of the means hereinafter fully described and 20 particularly pointed out in the claims.

The annexed drawings and the following description set forth in detail certain mechanism embodying the invention, such disclosed means constituting, however, but one 25 of various mechanical forms in which the principle of the invention may be used.

In said annexed drawings:-

Fig. 1 is a plan view of my machine; Fig. 2 is a side elevation of the same; Fig. 3 is 30 a side elevation showing the boom, bucket, and controlling means therefor; Fig. 4 is a section on the line 4—4, Fig. 1; and Fig. 5 is a section on the line 5—5, Fig. 1.

In Figs. 1 and 2 the general construction 35 of the machine may be seen, consisting of a rectangular framework 1 supported upon wheels 2 and 3, of which the wheels 2 are propelling wheels and the wheels 3 the steering wheels. The steering wheels 3, 40 which are at the rear, may be controlled by means of a steering column 4, worm 5 and gear 6, and a transversely extending shaft 7, over which is wound a chain 8 attached to either end of an axle 9 mounted in the two 45 opposite wheels 3.

On the floor or horizontal framework 1 of the machine is mounted an A frame, consisting of members 10, braced by means of a diagonal support 11 and forming an upper 50 support for a vertical rotatable mast 12, which is suitably mounted at its lower end in the floor of the frame. Supported upon suitable uprights 13 and 14, attached to the frame and to the diagonal brace 11 is a 55 canopy 15. The machine as so far described

is not essentially different from previous machines of this same general type.

Mounted on the floor of the machine at the rear is a suitable power means, such as a gas engine 16, with a cooling system 17 therefor, driving two power shafts 18 and 19, which are disposed in parallelism and transversely of the machine frame. The drive to these power shafts is through gears 20 and 21, and 24, 25 and 26, and the engine 16, with the power shafts 18 and 19 and winding drums 22 and 23 thereon, constitutes a two-drum hoisting engine which is in common use on a machine of this character. The drums 22 and 23 are loose on 70 the shafts 18 and 19 and may be thrown into engagement therewith by means of clutches 27 and 28, respectively, and the operating levers 29 and 30. The shafts 18 and 19 differ from the shafts of the ordinary 75 two-drum hoists only in being extended transversely across the frame, and there carrying friction heads 31 and 32, which are respectively keyed to the two shafts. Co-operating with these friction heads or clutch 80 members are loose members 33 and 34, which are adapted to be moved outward and away from the members 31 and 32, and into and out of engagement therewith. The members 33 and 34 carry sprockets 35 and 36 integral therewith.

In Fig. 4 the construction of the means for engaging and disengaging the sprockets 35 and 36 is shown. Similar means are used on each sprocket. The member 33, which is 90 rotatably and slidably mounted on the shaft 18 and carries the sprocket 35 is adapted to be moved into operative engagement with the friction head 31 by means of a collar 37 and slidable key 38. The key 38 is slidable 95 lengthwise on the shaft 18 in a slot which is formed therein, and may be moved inward against the collar 37 by means of a pin 39 rotatably mounted in a longitudinal opening in the end of the shaft and operated by means 100 of a screw 40 formed on its outer end and working in a threaded collar 41 attached to the frame. Attached to the outer end of the threaded member 40 is a lever 42, adapted, upon being swung in one direction, to work 105 the pin 39 inward to press the friction head 33 against the head 31, thus engaging the sprocket 35 on the shaft 18. A reverse movement of the lever 42 will permit the disengagement of the two frictional members 110

which constitute the clutch, and a similar construction is provided for engaging the clutch members 34 and 32 to fasten the sprocket 36 to the shaft 19. This similar means also employs a lever 43 connected by means of a rod 44 to the lever 42, while a similar pin 45 is provided, but having an oppositely threaded portion for engaging the clutch 34 upon the disengagement of the clutch 33.

The connection between the two levers 41 and 43 cause simultaneous operation of the two clutches, but in reverse directions so that one is disengaged when the other is engaged. 15 The rod 44, for operating the levers, is extended and connected to the shaft 46, operated by means of a hand lever 47, and movement of this hand lever in its two directions causes the above described operation of the 20 sprocket-engaging clutches.

Mounted beneath the frame of the machine is a propulsion shaft 60, (see Fig. 5), which is, in reality, two shafts driven by differential mechanism contained in a differential case 25 61 and operated by a single differential gear or sprocket 62 in the usual manner. On this shaft 60 are carried two sprockets 63, over which are mounted chains 64 for driving sprockets 65 carried on the driving wheels 20 2, both driving wheels being driven through the differential means and chains in the usual manner.

Mounted ahead of the shafts 18 and 19, and the drums 22 and 23, is a third shaft 66. 35 This shaft is provided with a sprocket 67 keyed thereto, and in substantial alignment with the sprockets 35 and 36 on the shafts 18 and 19. There is also a third drum 68 on this shaft 66, which may be thrown into 40 or out of engagement by means of a clutch 69 and operating lever 70, while two other drums 71 and 72 are mounted upon an extension 73 of this shaft 66, and may be thrown into engagement by means of a clutch 74.

45 There is a chain 80 passing over the sprockets 35 and 36 on the shafts 18 and 19, then down and around the lower side of the sprocket 62 driving the differential mechanism, and then up and around the sprocket 50 67 driving the third shaft 66. This chain then passes over two idle sprockets 81 and 82, of which the sprocket 81 is adjustably carried on a short link 83, the adjustment being secured by means of a turnbuckle 84, 55 which may be tightened to draw this sprocket away from the others and tighten the tension on the chain. In this way a drive is secured for all of the shafts and drums of the machine from a single chain and from a 60 single driving shaft, which is the shaft of the engine, without the use of any reverse gearing or of any transmission mechanism, such as is commonly used in these machines, and is to be avoided if possible because of 65 its extreme weight and complication. By

the operation of the lever either the sprocket 35 or 36 may be engaged for driving by the shafts 18 and 19, respectively, in this way securing either a forward or reverse drive of the chain 80. Thus, the machine may be 70 propelled in either direction by the operation of this chain, or the shaft 66 may be turned in either direction, thus operating the drums 68, 71 and 72 when properly engaged by their respective clutches. When the machine is 75 to be stopped and the boom is to be operated a clutch 85, which engages one of the driving sprockets 63 which drives one of the chains 64 extending to the driving wheels of the machine, is thrown out of engagement by 80 means of a lever 86, and in this way one of the wheels of the machine is disconnected. When so disconnected the differential mechanism is free to turn one portion of the shaft 60 as the other or connected sprocket 63 is 85 held against movement by the weight of the machine resting upon the wheel connected thereto.

The operation of the various drums and hauling lines in connection with the manipulation of the boom and hoisting mechanism is substantially the same as on other machines of this general type, and need not be described in detail. The present invention relates to the means for operating the drums 95 and propelling mechanism from a single engine and through the combined mechanism already described.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In a machine of the character described, the combination of a frame, traction wheels therefor, an engine, two driving elements operable thereby in opposite directions, a hoisting drum shaft, a differential shaft operatively connected to said traction wheels, and means operable in either direction by said engine through said two driving elements, said means being connected to operate said hoisting drum shaft and said differential shaft.

2. In a machine of the character described, the combination of a frame, traction wheels therefor, an engine, two driving elements operable thereby in opposite directions, a hoisting drum shaft, a differential shaft operatively connected to said traction wheels, and means operable in either direction by said engine through said two driving elements, said means being connected to operate said hoisting drum shaft and said differential shaft, and means adapted to operatively disconnect said differential shaft

from one of said wheels while permitting continuous operation of said shaft.

3. In a machine of the character described, the combination of a frame, traction wheels therefor, an engine, two driving elements operable thereby in opposite directions, a hoisting drum shaft, a differential shaft operatively connected to said traction wheels, and means operable in either direction by 10 said engine through said two driving elements, said means being connected to operate said hoisting drum shaft and said differential shaft, and means adapted to simultaneously connect one of said two driving elements from said engine and to disconnect the other thereof.

4. In a machine of the character described, the combination of a frame, traction wheels therefor, an engine, two power shafts operable by said engine in opposite directions, driving elements loose on said shafts but movable into engagement therewith, a hoisting drum shaft, a differential shaft operatively connected to said traction wheels, a 25 continuous driving belt operatively connecting said driving elements on said power shafts with said hoisting drum shaft and said differential shaft, and a single means adapted to move either of said driving elements on said power shafts into engagement with its respective shafts.

5. In a machine of the character described, the combination of a frame, traction wheels therefor, an engine, two power shafts operable by said engine in opposite direction, 35 driving elements loose on said shafts but movable into engagement therewith, a hoisting drum shaft, a differential shaft operatively connected to said traction wheels, a continuous driving belt operatively connecting said driving elements on said power shafts with said hoisting drum shaft and said differential shaft, a single operating lever having connection with said two driving elements, said lever being adapted to 40 move either of said driving elements into engagement with its respective shaft, and means adapted to disconnect one of said traction wheels from said differential shaft.

6. In a machine of the character described, the combination of a frame, traction wheels therefor, an engine, a propelling shaft operatively connected with said wheels, a hoisting shaft, and two oppositely rotating power shafts, driving and driven elements 50 on said shafts, a belt operatively connecting all of said elements, and means adapted to operatively connect either one of the driving elements on said power shafts with its respective shaft.

Signed by me, this 9 day of Aug., 1919.
HENRY C. BECKWITH.
